INDICATING CONDITION CONTROLLER

Lyman L. Hill, Jr., 1995 Summit Ave., St. Paul, Minn. 55105; James A. Odom, Jr., 874 66th Ave. N., Brooklyn Center, Minn. 55430; and Norbert T. Wolfe, 5348 10th Ave. S., Minneapolis, Minn. 55417

Filed Feb. 16, 1970, Ser. No. 21,448

Term of patent 14 years

Int. Cl. D10—04

U.S. Cl. D52—7

FIG. 1 is a front elevational view of an indicating condition controller showing our new design;

FIG. 2 is a left side elevational view of FIG. 1, the right, top, and bottom side elevations being identical therewith; and

FIG. 3 is a left side elevational view of FIG. 2 with portion cut-away on lines 3—3 showing the recessed dial contours.

We claim:

The ornamental design for an indicating condition controller, substantially as shown and described.
